UNITED STATES PATENT OFFICE.

JOHN P. BROPHY, OF CLEVELAND HEIGHTS, OHIO.

AUTOMATIC MACHINE.

1,343,344.

Specification of Letters Patent. Patented June 15, 1920.

Application filed December 6, 1917. Serial No. 205,732.

To all whom it may concern:

Be it known that I, JOHN P. BROPHY, a citizen of the United States, and a resident of Cleveland Heights, county of Cuyahoga, 5 and State of Ohio, have invented a new and useful Improvement in Automatic Machines, of which the following is a specification, the principle of the invention being herein explained, and the best mode in which I have 10 contemplated applying that principle so as to distinguish it from other inventions.

The present invention relates to improvements in automatic machines, and more particularly to improvements in the means for 15 supporting and feeding the cutting and forming tools, which are held in the turret head or tool slide, up to and away from the work.

In the usual form of automatic machines 20 it is customary to employ a single turret head in which the tools are supported, whereas in my improved form of turret head I employ a plurality of independent heads or supports for the tools thereby enabling 25 me to perform more and varied operations on the article being operated on, and, in this way increasing the usefulness and efficiency of the machine.

My improvement furthermore relates to 30 an efficient and simple means for accomplishing the relative movement of the two turret heads to and away from the work.

To the accomplishment of the foregoing and related ends, said invention, then, 35 consists of the means hereinafter fully described and particularly pointed out in the claims.

The annexed drawings and the following description set forth in detail certain mechanism 40 embodying the invention, such disclosed means constituting, however, but one of various mechanical forms in which the principle of the invention may be used.

In said annexed drawing:—

45 Figure 1 is a vertical section through the turret head of an automatic machine showing my improved operating means for feeding the tool supports.

Fig. 2 is a partial end view of an automatic machine, part of the machine being broken away to more clearly illustrate my 50 device.

Fig. 3 is a front view of the tool turret showing a number of tools in position and

Fig. 4 is an elevation of the tool turret with 55 the lathe frame in section.

The general character of my improvement may best be seen in Fig. 1 in which is shown a housing, adjustably mounted on the guides 2 of the lathe bed 3 of an automatic ma- 60 chine.

In one end of the housing 1 is slidably mounted a cylindrical member 4, constituting one of the tool slides which is held against rotation in the housing 1 by a key 5. 65 Disposed parallel to the axis of the member 4 and equidistant from the center thereof are holes 6 adapted to retain the tools for operating on the articles to be formed. I have shown four holes for tools in the member 4 70 but it is immaterial how many holes are provided as long as they correspond to the number of live spindles in the lathe head. The holes 6 in the member 4 are so placed as to align with the spindles in the head 75 when the spindle heads are in operative position. A cylindrical recess 7 is provided in the rear of the member 4 in which a driving member 8 is adapted to fit. A spiral channel or groove 9 is cut on the driving 80 member 8 in which a roller 10 is adapted to track. The roller 10 is retained in the member 4 by a stud screw 11 passing through the rear of the member 4 and acting as a bearing for the roller 10. By this means any 85 rotation of the driving member 8 will tend to force the member 4 either forward or backward, depending on the direction of rotation of the driving member 8. A thrust bearing 12 is provided in the upright sup- 90 port 13 of the housing 1.

Passing axially through the member 4 is a hollow shaft 14 held against rotation in the member 4 by means of a key 15. Mounted on the outer end of the shaft 14 are slides 95 or guide ways 16 on which are to be mounted various tools 17, adapted to the work they are to perform on the article to be operated on, which is held in one of the live spindles of the head stock.

100 Disposed between the supports 13 and 18 and surrounding the shaft is another driving member 19 which is provided on its interior with a spiral groove or channel 20 in which a roller 21 is guided. A stud 22 fastened to the shaft 14 retains the roller 21 in 105 position and acts as a bearing for same. A thrust bearing 23 is positioned in the sup-

port 18 thereby taking care of any end thrust which may occur when the machine is in operation.

Disposed to the rear of and parallel to the axis of the members 4 and 14 is a cam shaft 30 held in suitable bearings supported from the bed of the machine. A cam 31 is mounted on the shaft 30 and is engaged by a roller 32 carried on a yoked member 33. A bearing block 38 on the shaft 30 is slidably mounted between the two arms of the member 33 thereby facilitating the easy movement of the shaft and the member 33.

At the end opposite to the yoke the member 33 is fastened to an arm 34 by means of a pivot pin 36 passing through a slot 35 in the member 34. The member 34 is pivotally connected to the lathe bed 3. Passing longitudinally through the slot 35 in the member 34 and having bearings in each end thereof is a feed screw 37. The feed screw 37 is provided at its outer end with a squared head 70 which is adapted to be engaged by a wrench or other tool whereby rotation of the screw can be accomplished.

Adjustably secured to the outer end of the arm 34 is a rack 40 which engages a segmental gear 41 loosely mounted on the cam shaft 30.

An arm 42 integral with the segmental gear 41 is adjustably secured to another segmental gear 43 also loosely mounted on the cam shaft 30.

Adjustable engagement between the arm 42 and the gear 43 is accomplished by means of a concentric T slot 44 in the gear 43 and sliding block 45 clamping the arm 42 and the gear 43 together by means of the bolt 46 and the nut 47.

The rack 40 is held in engagement with the gear 41 by means of rollers 48 on an arm 49 supported from the cam shaft 30.

The relative position of the rack 40 and the arm or member 34 is adjusted by means of a squared block 49 adapted to slidably fit in the slot 35. The block 49 also has screw threaded engagement with the feed screw 37 and is provided at its outer end with a stud 50 which passes through a boss 50 on the end of the rack 40. The rack 40 is held on the stud 50 by means of a nut 51 which engages the threaded end 52 of the stud 50. By means of this construction it will be seen that by rotating the screw 37 the rack 40 will be moved either away from or toward the pivotal connection of the arm 34 to the lathe bed 3, depending on the direction of rotation of the screw 37, thereby controlling the length of movement of the rack 40 over the gear 41.

Mounted on or cut integral with the driving member 19 is a gear 60 which meshes with the segmental gear 43. Thus it will be seen that any rotation of the cam shaft 30 will cause the roller 32 on the arm 33 to be

operated by the cam 31 and will transmit a reciprocating movement to the arm 33, thereby rocking the arm 33 about its pivotal support. The movement of the arm 34 will transmit a reciprocating movement to the rack 40 which will in turn operate the segmental gear 41, and, through the arm 42, will operate the segmental gear 43, thereby rotating the driver 19 through the gear 60 thereon.

As will be more clearly seen in Fig. 1 the arm 33 terminates at its lower end in an elongated boss 61. The end of this boss 61 is adjustably fastened to an arm 62, identical to the arm 34, which is also pivoted to the lathe bed 3. A rack 63 is adjustably secured to the outer end of the arm 62 and meshes with a segmental gear 64 loosely mounted on the cam shaft.

The gear 64 operates another segmental gear 65 by means of an arm 66 adjustably connecting the gears 64 and 65, in a manner similar to the connection between the gears 41 and 43.

A gear 67 on the driving member 8 meshes with the segmental gear 65. Thus it will be seen that any movement of the arm 33 will through the operation of the two racks and sets of segmental gears either move forward or retract the members 4 and 14.

It is also obvious that by changing the relative position of the segmental gears 41 and 43 and 64 and 65 by changing the relative position of each set of gears about the cam shaft 30 in conjunction with the adjustable features of the racks 40 and 63 on the arms 34 and 62 it is possible to time the relative movements of the members 4 and 14 to suit the necessities of the operations required to be performed on the article being formed.

By the use of the improvement shown it is possible to employ two tools in each position of the turret head which will operate on the article being formed at the same time, one being supported from the holes 6 in the member 4 and the other from the slides 16 on the shaft 14, each tool being controlled independently of the other. By this means it is possible to turn out a more varied assortment of articles as the opportunity is presented for performing many more operations with different forms of tools than is possible with the former style of turret head in the same length of time.

I have illustrated a number of tools in position in Figs. 3 and 4 and it is obvious that I may employ different ones than those shown, depending on the requirements of the work being done.

Other modes of applying the principle of my invention may be employed instead of the one explained, change being made as regards the mechanism herein disclosed, provided the means stated by any of the follow-

ing claims or the equivalent of such stated means be employed.

I therefore particularly point out and distinctly claim as my invention:—

5. 1. In an automatic machine, the combination of a housing, a plurality of tool-carrying slides in said housing, driving means in one of said slides, driving means surrounding one of said slides, and means for imparting movement to each of said driving means. 45
2. In an automatic machine, the combination of a housing, a plurality of tool-carrying slides in said housing, means for preventing rotation of said tool-carrying slides, driving means mounted in one of said tool-carrying slides, driving means surrounding one of said tool-carrying slides, and means for imparting rotary movement to each of said driving means. 50
10. 3. In an automatic machine, the combination of a housing, a plurality of tool-carrying slides in said housing, means for imparting longitudinal movement to said tool-carrying slides and means for varying the movement of each of said tool-carrying slides. 55
15. 4. In an automatic machine, the combination of a housing, a plurality of tool-carrying slides movably mounted in said housing, a driving member mounted in one of said tool-carrying slides, a driving member surrounding another of said tool-carrying slides, means for imparting longitudinal movement from said driving members to each of said tool-carrying slides, a cam shaft mounted in said housing, a cam on said cam shaft, and means actuated by said cam for imparting movement to each of said driving members. 60
20. 5. In an automatic machine, the combination of a housing, a plurality of tool-carrying slides movably mounted in said housing, a cam shaft mounted in said housing, a cam on said cam shaft, and means actuated by said cam for imparting movement to each of said driving members. 65
25. 6. In an automatic machine, the combination of a housing, two concentric tool-carrying slides having relative longitudinal movement mounted in said housing, a cam shaft in said housing, a cam mounted on said cam shaft, adjustable power-transmitting means engaging said cam, and means for varying the longitudinal movement of said concentric tool-carrying slides. 70
30. 7. In an automatic machine, the combination of a housing, two concentric tool-carrying slides having longitudinal movement mounted in said housing, a cam shaft in said housing, a cam mounted on said cam shaft, power-transmitting means engaging said cam, a plurality of segmental gears loosely mounted on said cam shaft, adjustable driving means connecting said power-transmitting means and said plurality of segmental gears, a plurality of segmental gears loosely mounted on said cam shaft adjacent said first-mentioned segmental gears, adjustable means adapted to vary the relative positions of said segmental gears, and means in said housing for imparting movement from segmental gears to said concentric tool-carrying slides. 75
35. 8. In an automatic machine, the combination of a housing, a plurality of tool-carrying slides movably mounted in said housing, a cam shaft mounted in said housing, a cam on said cam shaft, and means actuated by said cam for imparting movement to each of said driving members. 80
40. 9. In an automatic machine, the combination of a housing, a plurality of tool-carrying slides movably mounted in said housing,

Signed by me, this 30 day of November, 1917.

JOHN P. BROPHY.
